UNITED STATES PATENT OFFICE.

JOHN A. PORTER, OF ST. LOUIS, MISSOURI.

CAR-COUPING.

SPECIFICATION forming part of Letters Patent No. 253,626, dated February 14, 1882.

Application filed October 7, 1881. (No model.)

To all whom it may concern:

Be it known that I, JOHN A. PORTER, of St. Louis, Missouri, have made a new and useful Improvement in Car-Couplings, of which the following is a full, clear, and exact description, reference being had to the annexed drawings, making part of this specification, in which—

Figure 1 is a view in perspective of a car-coupling having the improvement; Fig. 2, a sectional side elevation of the coupling; Figs. 3 and 4, views in perspective of the coupling-bolt; Fig. 5, a side elevation of the front end of one of the draw-heads, showing the bolt supported flatwise therein; and Fig. 6, a front view of a draw-head.

The same letters denote the same parts.

The coupling of the draw-heads of the present construction is effected by means of a double-headed bolt, the draw-heads being chambered out to receive the bolt-heads, and the bolt, after its insertion in the draw-heads, being held therein by turning it around, so as to bring the shoulders of the heads to bear against shoulders within the draw-head chambers. The bolt is provided with a handle, by means of which the bolt can be readily and safely manipulated. The handle can also be used, when desired, as an ordinary coupling-pin to couple an ordinary link, and in the present as well as other draw-heads, for the present improvement does not preclude the draw-heads with which it is used from being coupled in the customary manner.

Referring to the drawings, A represents a car-coupling of the usual description, saving as modified by the present improvement. The draw-heads B B' are chambered out at b b', forming shoulders b' therein. The mouths b² are elongated laterally.

C represents the coupling-bolt, having the heads c c, which are flattened to correspond to the shape of the mouths b². The coupling is effected by turning the bolt C into the position shown in Figs. 1, 3, 5, (in which position the bolt can be inserted in and be withdrawn from the draw-heads,) and inserting the bolt-heads in the chambers b of the draw-heads, and then turning the bolt around into the position shown in Figs. 2, 4, and so that the bolt-heads c c come against the shoulders b' and

prevent the bolt for the time being from being withdrawn from the draw-heads.

D represents the handle of the bolt. By means of it the operator can turn and adjust the bolt without exposing his hands between the draw-heads. It also serves to weight the bolt, so as to keep the latter properly in position for coupling the draw-heads, the handle for this purpose being so arranged and extended upon the bolt that its weight operates to turn the bolt in its bearings in the draw-heads and cause the bolt-heads to come opposite the shoulders b', and to prevent the bolt from being jostled sufficiently to uncouple. The handle should be extended in the direction of the longitudinal axis of the heads c c. This is essential, for to use an ordinary coupling-link in connection with the present draw-head the mouth b² must be elongated laterally rather than vertically, and the heads c c, when the coupling-bolt is locked in the draw-head, should bear against shoulders at the top and bottom, respectively, of the chamber in the draw-head, as herein shown.

The draw-heads are preferably shaped out at b' to make room for the handle D when the draw-heads come together. The draw-heads may also be recessed at b³ b³ for a similar purpose, the recesses b³ b³ being shaped as shown to provide rests for the handle to enable the bolt to be set and held in one draw-head, so that the bolt shall be in the proper position for entering the opposing draw-head, as seen in Fig. 5. An ordinary coupling link and pins can be used with the present draw-heads B B' for the purpose of coupling them; and the present bolt C, its handle D being of proper and uniform diameter, without any cross-bar or enlargement at its lower end to prevent its insertion in the hole b⁵, can be used in connection with an ordinary link, in such case the handle D being inserted in the pin-hole b⁵, and the bolt proper, C, serving to prevent the handle from dropping through the draw-head.

I do not broadly claim a double-headed coupling-bolt having a handle; but

I claim—

1. The combination of the draw-heads B B', having the laterally-elongated mouths b² and the shoulders b' at the top and bottom, re-

spectively, of the chambers b , and the bolt C, having the flattened heads $c c$, substantially as described.

2. The combination of the draw-heads B B', having the laterally-elongated mouths b^2 and the shoulders b' at the top and bottom, respectively, of the chambers b , and the bolt C, having the flattened heads $c c$ and the handle D, said handle being extended and shaped substantially as described.

3. The draw-head B, having the shoulder b^3 , shaped as shown, for the purpose of supporting the handle D of the bolt C, substantially as described.

JOHN A. PORTER.
